ATTORNEY

UNITED STATES PATENT OFFICE.

GEORGE S. HURST, OF GLASTONBURY, CONNECTICUT, ASSIGNOR TO THE J. B. WILLIAMS COMPANY, OF GLASTONBURY, CONNECTICUT, A CORPORATION OF CONNECTICUT.

ADVERTISING DISPLAY SCREEN.

Application filed February 1, 1923. Serial No. 616,227.

To all whom it may concern:

Be it known that I, GEORGE S. HURST, a citizen of the United States, and a resident of Glastonbury, in the county of Hartford, and State of Connecticut, have invented new and Improved Advertising Display Screens, of which the following is a specification.

My invention relates to the class of devices employed in connection with the display of merchandise to advertise the same, and an object of my invention, among others, is to provide a device of this class that may be arranged to describe different articles of merchandise, thereby avoiding the use of different structures for advertising different kinds of merchandise.

One form of screen embodying my invention and in the construction and use of which the objects herein set out, as well as others, may be attained, is illustrated in the accompanying drawings, in which—

Figure 1 is a view in elevation of my improved advertising screen showing the flaps opened out in the same plane.

Figure 2 is an edge view of the same showing in dotted lines the positions in which the different flaps may be placed.

Figure 3 is a top view showing the flaps folded in position for use.

Figure 4 is a perspective view of the screen placed in condition for use.

Figure 5 is a perspective view illustrating the manner of use to describe different articles of merchandise.

Figure 6 is a front view of the screen illustrating its use in connection with an article of merchandise different from that illustrated in Figure 4.

In the accompanying drawings the numeral 7 denotes a back piece, that is composed of any suitable material, as cardboard, such back piece having a main flap 8 hinged thereto at its upper end so that said main flap may be folded in a position in front of the back piece or in a position back of the same. The front face 9 of the back piece, this being said face shown in Figure 1, is designed to receive any suitable advertising matter in connection with merchandise, as for instance, tooth paste. The front face 10 of the main flap 8 which will be that face located at the front when said flap is folded and placed in front, as shown in Figure 6, is designed to receive any suitable display

matter for some other kind of merchandise, 55 as for instance, shaving soap.

Side wings 11—12 are hinged to opposite side edges of the back piece 7, and these side wings are intended to receive upon their front faces display matter, which may be 60 for the same kind of goods as described on the front of the back piece, or which may be for goods of another variety.

Supplemental side flaps 13—14 are hinged to the top edges of the side wings 11 and 12 65 so that they may be folded down against the back of the said wings 11 and 12, and as illustrated in Figure 4, or they may be folded in front of said side wings when desired, and as illustrated by one of said flaps 70 shown in Figure 5. The front faces 15—16 of the supplemental flaps, which will be those surfaces toward the observer when said flaps are located in front of the side wings, are intended to receive any suitable display 75 matter for advertising a variety of goods other than that described on the front face of the side wings.

Preferably, in the use of my improved screen, the back piece and the side wings 80 will be used for display purposes in connection with merchandise of a certain kind, and the display faces of the main flap and the supplemental side flaps will be employed for display purposes in connection with merchandise of another sort. It will thus be seen that my improved screen, comprising a single structure, may be employed for display purposes in connection with two or more articles of merchandise, the screen commonly being set upright adjacent to or among the said articles, the faces of the wings describing such articles being toward the front. The flaps may afterward be positioned to describe another article of merchandise and the screen then placed with the display of such articles, or different kinds of merchandise may be arranged in a single display, or in adjacent displays, and the flaps when properly arranged will serve to 90 function with the different varieties of goods. 95

I claim—

1. A display screen comprising a back piece, side wings hinged thereto, and a flap hinged to the upper edge of each side wing 105 and foldable thereover for assuming positions either forwardly or rearwardly of the back piece and side wings.

2. A display screen comprising a back piece, side wings hinged thereto, and a flap hinged to the upper edge of the back piece and each side wing and foldable thereover for assuming positions either forwardly or rearwardly of the back piece and side wings.
3. A display screen comprising a back piece, side wings hinged thereto, and a flap

hinged to the upper edge of the back piece and each side wing and foldable thereover for assuming positions either forwardly or rearwardly of the back piece and side wings, the side wings being of less height than the back piece and said flaps being of the same length as the members carrying the same.

GEORGE S. HURST.
